Nelson M. Howard

UNITED STATES PATENT OFFICE.

ALBERT E. HUDSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

NAIL DISTRIBUTOR.

Application filed February 12, 1923. Serial No. 618,591.

To all whom it may concern:

Be it known that I, ALBERT E. HUDSON, a citizen of the United States, residing at Beverly, in the county of Essex and State of Massachusetts, have invented certain Improvements in Nail Distributors, of which the following description, in connection with the accompanying drawings, is a specification, like reference characters on the drawings indicating like parts in the several figures.

My invention relates to nail-distributors, and more especially concerns, in such apparatus, the discharge mechanism generally organized in the manner disclosed in the application for Letters Patent filed in the name of Frederick J. Balcom on September 2, 1921, and bearing the Serial Number 498,074. In this arrangement, the discharging member or rotatable roll, which receives nails from a raceway and delivers them in successive charges to the machine supplied, has, co-operating with it, a bar or other stop member, which temporarily retains the nails upon the roll until a charge has accumulated, and then yields under the influence of the rotation of said roll to permit delivery. The stop-bar is adjustable, in an approximately horizontal direction, toward and from nail-receiving openings in the roll to properly position nails of different lengths, and, normally, its inner edge lies over a nail-directing surface, which continues the support afforded by the walls of the openings in the roll. It has been found desirable to have not only the openings, but also the continuing walls, inclined downwardly in the direction of delivery to facilitate the advance of the nails during their reception by the roll and their positioning by the bar, and to prevent accidental displacement by changes in their course. This inclination causes the directing surface to diverge downwardly from the plane to which the stop-bar is adjusted, and in the forward movement of the latter from the roll-openings a space may be opened between it and the directing surface, through which space the nails may pass without being arrested; or, if the nails are held by the bar, may lead to their premature release when the delivery movement of the roll begins.

It is an object of this invention to provide, in a nail-distributor having a dis-

charge device of the character mentioned, for such a relation between the stop member and the discharge device, as to under all conditions produce a correctly timed delivery of the nails. To attain this result, the stop member or bar is not only movable toward and from the discharge device or roll in accordance with the length of the nails acted upon, but also in another direction, so as to control its normal relation to the directing surface, and thus compensate for the divergence between the member and the co-operating surface of the roll. The stop member is shown as being a composite device, including a body-portion or plate adjustable toward and from the openings in the discharge device, and a stop-bar, which receives the contact of the nails and which may be adjusted upon the body-portion. Preferably, between this body-portion and stop-bar is a carrier member or slide, arranged to yield upon the body-portion, and to which the stop-bar may be pivoted for its independent adjustment. This interposed yieldable member permits of the actuation of the stop member by the discharge-roll in its rotation.

A particular form which this invention may assume is illustrated in the accompanying drawing.

Fig. 1 being a side elevation of the forward portion of a nail-distributing apparatus to which my improved discharge mechanism is applied;

Fig. 2, a broken top plan view of the same part of the apparatus;

Fig. 3, a similar view, enlarged, showing a portion of the apparatus only;

Fig. 4, an enlarged vertical section on the line 4—4 of Fig. 2, illustrating the elements in the nail-receiving position; and

Fig. 5, a like view, showing the discharging position.

The general nail-distributing organization may be similar to that disclosed in Patent No. 1,005,303, Pope, October 10, 1911. This includes a nail-conveyor or raceway 10 arranged to oscillate upon a frame 12 and provided with inclined grooves or nail-ways 14 carrying the nails from a drum or container (not illustrated) in series in each of the ways, as appears at N in Fig. 4 of the drawing, to the discharge mechanism D. The discharge device proper consists of a

roll 16 journaled horizontally for rotation upon the forward end of the conveyor-frame. This roll is oscillated from the nail-receiving position, shown in Fig. 4, to the nail-discharging position, illustrated in Fig. 5, by a crank-arm 18 fixed to the spindle of the roll and operated through a link 20 and a lever 21 from a cam 22 upon a shaft 23, this shaft being constantly rotated while the apparatus is in action. Co-operating with the nail-ways are the usual stop-fingers 24, oscillated from a cam on the discharge-roll-spindle to alternately release the nails to permit their travel down the nail-ways to the discharge mechanism, and to check this advance while said discharge mechanism is operating.

Extending longitudinally of the axis of the discharge-roll is a recess 25, which, approximately, has the form produced by removing from the roll a sector of about 105 degrees. In the normal or nail-receiving position of the roll (Fig. 4), a wall 26 of the recess is inclined downwardly from the horizontal, while the other wall 28 extends substantially vertically. Opening through the wall 28 and through the opposite side of the roll is a series of transverse perforations 30, corresponding in number to the nail-ways, being alined with them, and having the same inclination when the discharge-roll occupies the nail-receiving position. This inclination is continued by grooves 31 in the directing surface 26, a convenient manner of producing these grooves being by drilling them simultaneously with the openings 30. It will be seen that when the series N of nails are released by the elevation of the fingers 24, a continuous downwardly sloping surface is afforded, along which the nails travel until they are stopped by the device hereinafter described. Since there is no change in the direction of their travel, they proceed, without liability to displacement by the vibration of the machine, this maintenance of their true relation being aided by the presence of the grooves 31, which afford them lateral support. In the opposite extreme position of the roll, illustrated in Fig. 5, the perforations and alined grooves are so inclined that they will discharge the contained nails by gravity into conduits 33 leading to the loading mechanism of the machine, as a heeler, which is to be supplied. Entering the roll-recess 25, so that it lies in the path of movement of the roll in its rotation, is a stop member, shown in the form of a bar 32. This bar preferably is parallel to the axis of the roll 16, and has a stop-surface 34, approximately perpendicular to the directing surface 26, the stop-surface extending across the forward ends of the perforations 30. At each end of the bar 32 is an arm 36, pivoted at the opposite ex-

tremities of a carrier member or bar 38 situated just in front of the bar 32, and having a forwardly extending portion 40 arranged to slide in a way 42 in a plate 44, furnishing the body-portion of the stop device and carried upon the conveyor-frame. The plate 44 is mounted for adjustment toward and from the discharge-roll, to change the distance between the surface 34 of the stop-bar and the openings 30 in the roll, by a shaft 46, journaled in the conveyor-frame, arranged to be turned by a hand-wheel 48, and having pinions 50, 50 meshing with series of rack-teeth 52, 52 upon the upper face of the plate. The stop-bar is pressed yieldably into the recess in the discharge-roll by springs 54, two of which may be employed, these springs being contained in bores at the outer edge of the plate. The forward extremities of the bores are threaded to receive screw-plugs 56, against which the inner ends of the springs abut. By turning these plugs, the force with which the springs resist the movement of the stop-bar may be varied. The intersection of the wall 28 with the cylindrical surface of the roll 16 furnishes a cam or contact-projection 58 arranged to strike, in the oscillation of the roll, upon the stop-surface 34 of the bar. This engagement forces the stop-bar and carrier-bar away from the roll, as is illustrated in Fig. 5, the springs 54 yielding to permit this, until the path of the nails carried upon the surface 26 is cleared, and they drop into the delivery-tubes.

Threaded through the center of the rear portion of the carrier-bar 38 is a vertical screw 60, having a finger-piece or head 62, by which it may be rotated to raise or lower it in the bar. It may be fixed in its adjusted position by a lock-nut 64 bearing against the upper surface of the bar. At its lower extremity is a flange or enlargement 66, the edge of which enters a recess 68 in the adjacent wall of the stop-bar. When the lock-nut is loosened, the screw may be turned, so that its portion 66, acting upon the bar, will either raise or lower this, and thus change its normal relation to the surface 26 of the discharge-roll. When the desired adjustment is obtained, the screw may be locked in position by the nut.

In using this discharge device, the stop-bar 32 is adjusted in a substantially horizontal direction by moving the body-portion 44 through the gearing 50, 52 until the wall 34 is in such a position that the contact of the forward ends of the nails, as they lie in the openings 30 and grooves 31, will bring the opposite extremities just outside the periphery of the roll to hold the succeeding nails in the ways 14 spaced from said roll. This is as illustrated in Fig. 4. If a shorter nail is to be operated upon, the shaft 46 will

be turned to bring the wall 34 nearer to the forward ends of the openings 30, or if longer nails are to be used, the stop member will be moved by its gearing in the opposite direction. If the first-mentioned change in location of the stop-bar is to be made, the screw 60 will be turned to lift the bar, the final adjustment being such that the lower edge of the bar will just clear the surface 26 between the grooves 31. When adjustment is made for a longer nail, the stop-bar will be lowered, the space between its lower edge and the surface 26 being kept constant for all horizontal positions. As the roll oscillates in the direction of the arrows in Figs. 4 and 5 to discharge the nails, the cam-projection 58, operating against the stop-surface 34, forces the bar forward, the springs 54 yielding. Thus, the roll moves the bar out of its path, as is particularly shown in Fig. 5, leaving said roll free to complete its oscillation. This at once carries the stop-surface away from the extremities of the nails resting in the grooves 31, so that there is nothing to prevent their discharge into the receiving conduits, into which they fall by gravity. As the reverse movement of the roll occurs, the springs 54 cause the bar to follow the projection 58 back to the normal position, whereupon the nail-receiving and discharging operation is repeated.

Having described my invention, what I claim as new and desire to secure by Letters Patent of the United States is:

1. In a nail-distributor, a movable discharge device for the nails, a stop member for temporarily retaining the nails upon the device and being movable toward and from said device, and means arranged to move the stop member in another direction.

2. In a nail-distributor, a movable discharge device for the nails, a stop member for temporarily retaining the nails upon the device and being movable toward and from said device, means for effecting the movement of the stop member, said member also being movable under the influence of the discharge device, and means arranged to move the stop member in another direction.

3. In a nail-distributor, a movable discharge device having a directing surface over which the nails pass, a member located over the directing surface for temporarily stopping the travel of the nails upon such surface and being movable to free said nails for delivery, and means arranged to control the normal distance of the stop member above the directing surface.

4. In a nail-distributor, a movable discharge device having a surface downwardly inclined in the direction of discharge of the nails, a stop member co-operating with the surface and being movable in a direction diverging therefrom, and means arranged

to move the stop member toward and from the surface to compensate for such divergence.

5. In a nail-distributor, a movable discharge device for the nails, a stop device having a body-portion, means for adjusting the body-portion horizontally toward and from the discharge device, a member mounted upon the body-portion and with which the nails contact, and means arranged to adjust the position of the member vertically upon the body-portion.

6. In a nail-distributor, a movable discharge device for the nails, a stop device having a movable body-portion, a carrier member movable upon the body-portion, and a stop member movable upon the carrier member and arranged to contact with the nails upon the discharge device.

7. In a nail-distributor, a movable discharge device for the nails, a stop device having a body-portion, means for adjusting the body-portion toward and from the discharge device, a carrier member yieldable upon the body-portion, a stop member movable upon the carrier member, and means for adjusting the stop member upon the carrier member in a different direction from that furnished by the adjustment of the body-portion.

8. In a nail-distributor, a rotatable discharge-roll having nail-receiving openings and a nail-directing surface to which the nails pass from the openings, a stop member arranged to receive contact of the forward extremities of the nails while said extremities are upon the directing surface, and means arranged to impart to the stop member movements in a plurality of directions.

9. In a nail-distributor, a rotatable discharge-roll having nail-receiving openings and a nail-directing surface to which the nails pass from the openings, and a stop member movable over the surface toward and from the openings, said member also being movable toward and from the surface.

10. In a nail-distributor, a rotatable discharge-roll having nail-receiving openings and a directing surface inclined downwardly in the direction of travel of the nails, a stop member movable over the surface in a generally horizontal direction, and means arranged to adjust the member toward and from the directing surface independently of such horizontal movement.

11. In a nail-distributor, a rotatable discharge-roll having nail-receiving openings and a nail-directing surface to which the nails pass from the openings, a stop member yieldably mounted to move over the surface from the openings, means arranged to adjust the stop member toward and from the openings, and means arranged to adjust the stop member toward and from the surface.

12. In a nail-distributor, a rotatable discharge-roll having nail-receiving openings and a nail-directing surface to which the nails pass from the openings, a stop member yieldably mounted for movement by the discharge-roll from the openings, means arranged to adjust the stop member toward and from the openings, and means arranged to adjust the stop member toward and from the surface.
13. In a nail-distributor, a rotatable discharge-roll, a movable plate adjacent thereto, and a bar mounted to slide upon the plate, said bar having movable upon it a portion for contact with the nails.
14. In a nail-distributor, a rotatable discharge-roll, a movable plate adjacent thereto, a carrier-bar mounted to slide upon the plate, and a bar pivoted upon the carrier-bar for contact with the nails.
15. In a nail-distributor, a rotatable discharge-roll, a movable plate adjacent thereto, means for moving the plate toward and from the roll, a carrier-bar yieldable upon the plate and movable by contact with the roll, a bar pivoted upon the carrier-bar for contact with the nails, and connections between the carrier-bar and contact-bar for moving the latter.
16. In a nail-distributor, a rotatable discharge-roll having nail-receiving openings and a directing surface inclined downwardly in the direction of travel of the nails, a movable plate adjacent to the roll, means arranged to adjust the plate toward and from the openings, a carrier-bar movable upon the plate under the influence of the roll in its rotation, a bar movable upon the carrier-bar over the inclined surface and contacting with the nails, and connections between the carrier-bar and contact-bar for raising and lowering the latter.

In testimony whereof I have signed my name to this specification.

ALBERT E. HUDSON.
